MANUFACTURE OF TETRAALKYLLEAD

Hymin Shapiro, Detroit, Mich., assignor to Ethyl Corporation, New York, N. Y., a corporation of Delaware

No Drawing. Application May 29, 1948,
Serial No. 30,191

6 Claims. (Cl. 260—437)

1

This invention relates to a catalytic process for the manufacture of tetraalkyllead from magnesium-lead alloy and certain of the alkyl halides. More particularly, it relates to a process for reacting a magnesium-lead alloy with an alkyl halide selected from the group consisting of chlorides, bromides, iodides in the presence of selected catalysts to form a tetraalkyllead.

The manufacture of tetraethyllead is of considerable importance because of its use as an antiknock agent in motor fuels. It is used in most of the gasolines presently marketed. Therefore, the economics of its manufacture is also of major importance.

The present commercial process for the manufacture of tetraethyllead has been used for a number of years, and, in general, is satisfactory. However, it has certain disadvantages which are overcome by practicing my invention. The present commercial process is expressed by the following chemical equation:

In the process as illustrated in the above equation, if the composition of the alloy is controlled to correspond substantially to NaPb, the reaction goes readily to completion without a catalyst and tetraethyllead yields of about 21 per cent by weight based on the lead input are obtained.

It is to be noted, however, that in the NaPb reaction, less than one-quarter of the lead originally present in the alloy is converted to tetraethyllead. The remaining three-quarters of the original lead present is converted to finely divided metal considerably contaminated with the product. The presence of this large amount of unused lead in the autoclaves makes temperature control difficult, results in a low overall rate of product output, and necessitates a relatively large investment in equipment as compared with the more efficient processing of lead obtainable in practicing my invention. Furthermore, the conversion of the finely divided lead to a form suitable for use in making the NaBb alloy is a hazardous and expensive operation.

It is an object of this invention to provide a process for making tetraalkyllead overcoming the above objections, particularly in making more efficient use of the lead. This is accomplished in my invention by reacting certain alkyl halides with magnesium-lead alloy in the presence of a catalyst, as illustrated by the following chemical equation:

It is to be noted that in the above equation, no lead in the alloy is converted to metallic lead as contrasted with over 75 per cent lead converted from the alloy to finely divided metal in the present commercial operations.

2

The above reaction is carried out in the presence of catalysts. While neither the exact mechanism of the reaction nor the effect of catalyst structure on the reaction is known, I have found that organic carbon compounds containing an atom capable of chemical coordination with a magnesium-containing compound are the most effective. Among the catalysts having such properties are aliphatic ethers, tertiary amines including aliphatic and aromatic tertiary amines, and hydrocarbon-substituted ammonium iodides, including aliphatic- and aromatic-substituted ammonium iodides. In all the compounds coming within the above groups, the coordinating atom is either oxygen or nitrogen.

Catalysts that can effectively be used in my process are the aliphatic ethers, such as methyl ether, ethyl ether, propyl ether, isobutyl ether, and hexyl ether. Also, both aliphatic and aromatic amines or mixtures thereof produce good results. Examples of the amines are trialkyl amines, such as triethyl amine, tripropyl amine, tributyl amine, alkyl phenyl amines, such as dimethyl phenyl amine, diethyl phenyl amine, and methyl diphenyl amine. Also, amines such as pyridine have been successfully used. High yields of tetraalkyllead compounds have been obtained using alkyl or aromatic ammonium iodides such as trimethylphenyl ammonium iodide, tetrabutyl ammonium iodide, and tetraethyl ammonium iodide.

Alkyl halides selected from the group consisting of chlorides, bromides, and iodides can be used to react with the Mg₂Pb alloy to form the corresponding tetraalkyllead compounds, such as the monochloro derivatives of methane, ethane, propane, butane, and pentane, as well as the corresponding bromides and iodides. For example, ethyl chloride, ethyl bromide, methyl bromide, isopropyl bromide, isobutyl bromide, and n-butyl iodide have been successfully employed.

My process can be carried out at temperatures up to 150° C. although the preferred range is 80° C. to 120° C. Pressures from a few pounds above atmospheric to several hundred pounds per square inch can be employed advantageously. Best yields are obtained by using an alloy corresponding to Mg₂Pb (19.01 per cent Mg by weight), but good yields are obtainable with a magnesium content varying from 18 to 22 per cent by weight. As the magnesium content varies outside of this range inferior results are obtained, and furthermore, the alloy is more difficult to crush preparatory to using.

The time for the reaction can also be varied over a wide range. In closed bomb operations, the reaction time has been varied between two and sixteen hours with good results. The amount of catalyst can also be varied within wide limits, i. e., between 1 and 130 per cent by weight of the

alloy charged has been used. The proportion of the particular catalyst used, and the operating conditions of temperature, pressure and time will vary with the alkyl halide used in order for optimum results to be obtained, and such variables need to be correlated to obtain high yields of tetraalkyllead compounds.

My invention is further illustrated by the following example: 10 grams of Mg₂Pb alloy, 20 grams of ethyl chloride and 5 grams of ethyl ether catalyst were introduced into a "tumbled" bomb. The alloy, comprising about 19 per cent by weight magnesium, was first ground in a "chipmunk" crusher to a particle size varying from four to 100 mesh, substantially three-quarters of the ground alloy being in the range of four to 40 mesh. The ethyl chloride and the ether are ordinary commercial grades. The materials are charged into the bomb preferably in the order: alloy, ethyl chloride, and ethyl ether. The bomb was then closed off and tumbled for six hours at 80° C. The reaction is exothermic and cooling is employed after the reaction is under way in order to maintain the desired temperature. In this experiment, the temperature was controlled by the controlling of the temperature of the bath in which the bomb was immersed. In commercial practice, cooling water suitably applied can be used. The pressure in this experiment reached a maximum of 80 pounds per square inch. At the end of six hours, the bomb was cooled and the product analyzed for tetraethyllead. Again, in commercial operations the product can be distilled in vacuum or in the presence of steam to recover the tetraalkyllead product. In this example, an analysis showed that 6.07 grams of tetraethyllead were produced, which is equivalent to 45 per cent by weight, based on the lead input as compared with the 21.0 per cent obtained in present commercial operations using NaPb alloy.

The results of the above experiment are tabulated as Example No. 1 in the table given below,

entitled "Summary of Experiments." The results of twenty-three additional experiments conducted in a similar manner are also tabulated in the table. In all the examples, 10 grams of Mg₂Pb alloy, comprising about 19 per cent by weight magnesium was used. The twenty-four examples illustrate results obtained with different alkyl halides added in varying amounts, different catalysts added in varying amounts, and different operating conditions with tetraalkyllead yield varying from 25 to 85 per cent by weight based on the lead input.

Referring to the table, Column 1 gives the example number; Columns 2, 3 and 4 refer to the alkyl halide; Column 2, the name, Column 3, the theories, and Column 4, the grams charged. The theories are the ratio of alkyl halide charged to the theoretical amount required for the lead to be completely reacted. Columns 5, 6, and 7 refer to the conditions of operation; Column 5, to the length of time the reactants remained in the bomb; Column 6, to the temperature maintained during reaction, and Column 7, to the pressure in pounds per square inch. The pressure in the experiments tabulated was not controlled, but was the pressure resulting from the materials charged at the temperature under which the bomb was maintained. Again referring to the table, Columns 8, 9, and 10 relate to the catalyst used, Column 8 to the name; Column 10 to the grams charged, and Column 9 the per cent by weight of catalyst based on alloy charged. Columns 11 and 12 relate to the tetraalkyl product; Column 11, to the grams recovered, and Column 12 to the percentage yield based on the lead in the alloy charged.

In Examples 1 to 20, inclusive, single catalysts were used. In runs 21 to 24, inclusive, double catalysts were used. It should be noted that, in general, the yield increased by using a double catalyst. The use of single or multiple catalysts depends principally on the alkyl halide charged and the desired conditions of operation.

Summary of experiments

Ex- ample No.	Alkyl Halide				Conditions			Catalyst			Yield	
	Name	Theo- ries	Grams	Time, Hours	Temp., °C.	Pressure Lbs. per Sq. In.	Name	Per cent	Grams	Grams	Per cent

						83	Ethyl Ether	5	0.5			
						138	(Tetrathylammonium Iodide	16.5	1.65	5.74	45.4	

It is to be noted that without a catalyst the yield of lead alkyls is inferior to those given herein. For example, when alkyl chlorides are used as the alkylating agents, the yields obtainable without a catalyst are insignificant. When alkyl bromides or alkyl iodides are used as the alkylating agents, increased yield attributable to the catalyst amounted to from 20% to about 50%.

As pointed out previously, the catalysts of my invention comprise organic compounds containing compound. Therefore, my catalyst is an organic, chemical coordination catalyst which is defined in the above terms.

In all cases, an excess of alkyl halide over the theoretical amount required is preferred. Not only does an excess increase the yield, but also it increases the rate of production which is important in commercial operation because it reduces equipment size and cost. Also, an excess of halide maintains a liquid which provides for better heat transfer in maintaining by cooling, the desired temperature of operation.

The examples given herein are illustrative of my invention, but do not limit the scope of my invention. The reaction can be carried out in batch or in continuous operations. The manner of operation, as well as the equipment used can be varied considerably within the scope of my invention.

I claim:

1. A process for making tetraalkyllead comprising alkylating lead in an alloy consisting of lead and magnesium in the presence of an alkylating catalyst containing an atom which chemically coordinates with magnesium.
2. A process for making tetraalkyllead comprising reacting a lower alkyl halide with an alloy consisting of lead and magnesium in the pres-

ence of a catalyst selected from the group consisting of aliphatic hydrocarbyl ethers, tertiary hydrocarbyl amines and tetrahydrocarbyl ammonium iodides.

3. A process for making tetraalkyllead comprising reacting a lower alkyl halide with an alloy consisting of lead and magnesium in the presence of an aliphatic hydrocarbyl ether.

4. A process for making tetraethyllead comprising reacting an ethyl halide with an alloy consisting of about 18 to 22 per cent by weight magnesium and about 78 to 82 per cent by weight lead in the presence of a lower dialkyl ether.

5. A process for making tetraethyllead comprising reacting ethyl chloride with an alloy consisting of about 18 to 22 per cent by weight magnesium and about 78 to 82 per cent by weight lead in the presence of diethyl ether.

6. A process for making tetraethyllead comprising reacting ethyl chloride with an alloy consisting of about 19 per cent by weight magnesium and about 81 per cent by weight lead in the presence of diethyl ether.
